FOLDING TIRE WRENCH

Clark M. Bolser, Cedar Falls, Iowa, assignor to Champ Products Co., Cedar Falls, Iowa, a copartnership

Application January 30, 1956, Serial No. 39,964

Term of patent 14 years

(Cl. D54—16)

Fig. 1

Fig. 2

Fig. 3

Fig. 4

Fig. 1 is a perspective view of a folding tire wrench showing my new design, the wrench being in folded position;

Fig. 2 is a perspective view of the reverse side of the wrench, the wrench being in the non-folded position;

Fig. 3 is a side elevation of Fig. 1; and

Fig. 4 is a side elevation of Fig. 2.

I claim:

The ornamental design for a folding tire wrench, substantially as shown.
